OUTBOARD MOTOR

Finn T. Irgens, Wauwatosa, Wis., assignor to
Outboard Motors Corporation, Milwaukee, Wis.,
a corporation of Michigan

Application June 14, 1934, Serial No. 730,545

8 Claims. (Cl. 115—18)

This invention relates to improvements in outboard motors, and has particular reference to the parts which connect the engine or power head with the lower unit.

5 It is the object of the invention to provide means for simplifying the construction of a drive shaft housing and associated parts, eliminating irregularities, and providing a smoother, neater, and more attractive organization without interfering with the exhaust or water pipes in the

10 normal steering movement of the parts. More specifically, it is a purpose of the invention to carry the smooth wall surfaces of a streamlined lower unit upwardly past the bracket to a hooded power head by providing a complementary exhaust pipe and swivel housing joint upon the radius on which the drive shaft housing turns within the swivel housing, so that the exhaust pipe and the shaft housing connecting the power head and lower unit can turn freely with respect to the swivel housing member but will nevertheless be so formed and organized that in the normal position of the parts the assembly will appear unitary and smooth walled.

15 25 It is another object of the invention to provide a novel organization of exhaust and water passages, and also to provide an improved organization of the swivel bearing with reference to the transom bracket.

30 In the drawing:

Figure 1 is a side elevation of an outboard motor embodying this invention.

Figure 2 is a view taken in section in the plane indicated at 2—2 in Figure 1.

35 Figure 3 is a view taken in section in the plane indicated at 3—3 in Figure 1.

Figure 4 is a fragmentary vertical section taken in the plane indicated at 4—4 in Figure 2.

40 Figure 5 is a view similar to Figure 3 illustrating a slightly modified embodiment of the invention and showing the parts in a position turned for steering.

Like parts are identified by the same reference characters throughout the several views.

45 It will be noted that the lower unit 5 is of a streamlined form which is now well known. To it is attached a correspondingly streamlined section at 6 in which the water pump mechanism is conventionally housed.

50 55 At the upper end of the outboard motor is a power head in which projecting gadgets have been eliminated and the design unified by an arrangement such that the forward face 7 of the cylinder block 8 has a planiform portion abutted by the hood 9 which encloses the usual

spark plugs and carburetor. At the rear of the cylinder block is a muffler 10 harmonized as to design with the hood 9 and the end of the cylinder block 8. Above this is the usual fuel tank 11 in front of which a hood 12 covers the fly-wheel and starter.

In the past the portion of a dirigible outboard motor between the power head and the lower unit has been irregular of surface and unsightly in appearance, presenting numerous crevices and pockets in which grease and dirt may accumulate when the motor is in use and in which branches may catch when the motor is being carried.

In the present device the power head is mounted in the usual manner at the upper end of a drive 15 shaft casing 15 through which extends the upright drive shaft 16 leading from the engine to the propeller shaft gearing which is conventional and hence is not illustrated. The tubular drive shaft housing 15 serves in the usual way to connect the power head with the lower unit so that these parts turn unitarily for steering.

Also serving as a connection between the power head and the lower unit, is the exhaust pipe 17 which, instead of being circular in cross section 25 in accordance with the usual practice, has the peculiar form best shown in Figs. 2 and 3. Its exterior wall surfaces are rearwardly convergent and preferably convex, so that the appearance of the external portion of the exhaust pipe 17 corresponds to that of the rear portion of a streamlined body. Its forward wall 18, however, is concave upon an arc drawn about the axis of the drive shaft 16 as a center, this being the axis upon which the dirigible parts turn for steering. 30 35

The sleeve 20 which serves as a swivel sleeve in which the outboard motor turns for steering, has at 19 a surface convexly complementary to the concave wall 18 of the exhaust manifold. Its exterior wall surfaces will, in the normal position 40 of the dirigible parts, align with the exterior wall surfaces of the exhaust manifold to provide forward extensions of the streamline effect, as clearly appears from Figs. 2 and 3.

At the upper and lower ends of the swivel 45 housing 20 the swivel housing is provided with bearings for the support of the outboard motor assembly for rotation in steering. The construction is preferably in accordance with United States Patent No. 1,932,785, a rubber cushion being provided at 21 between the swivel housing 20 and the shaft housing 15, and a second rubber cushion being provided at 22 between the shaft housing 15 and the sleeve 23 to which the tiller lever 24 is fixed, the tiller sleeve 23 being 50 55

swiveled in the upper end of swivel housing 20 to be held against vibration thereby, notwithstanding such independent vibration of the outboard motor assembly as is permitted by the 5 cushions 21 and 22. The internal and external peripheral portions of the cushion 22 may be anchored by vulcanization or otherwise to the shaft housing and the tiller sleeve respectively, so that the movement of the tiller and tiller 10 sleeve will be transmitted to the outboard motor assembly for steering purposes.

The swivel housing 20 has a forwardly projecting arm at 25 which is pivoted at 26 in the usual manner to a transom bracket 27. This bracket 15 preferably omits entirely the conventional rearwardly projecting segment arms, and in lieu thereof is machined between its reinforcing flanges 28 to provide a box-like recess into which the forward portion of the swivel housing 20 is 20 receivable to a greater or less depth according to the position of the adjustable thrust bolt 29 in one of the several apertures 30 provided in the flanges 28.

It will be noted that the swivel housing 20 is 25 made in two parts in accordance with the teachings of Patent No. 1,932,785 above referred to, the lower wall surfaces of the forward part being streamlined at 32 in accordance with the wall surfaces of the rearward part as already described. Between the flanges 28 of the bracket, however, the wall surfaces of the forward portion of swivel housing 20 are preferably substantially rectilinear in section as shown at 33 in Fig. 2.

35 It is preferred that in this construction the water connections should be led to the engine through the exhaust manifold 17. An ordinary pipe may be used as shown at 34 or, if the exhaust manifold be cast, an internal partition 40 may be provided as indicated at 35 to provide a water passage 36 as shown in Fig. 5.

Figs. 1 to 4 inclusive show the parts in their 45 normal forward propulsion position, and it will be noted how successfully the streamlining of the lower unit is carried up about the shaft housing to the power head. Notwithstanding the effect thus produced in the normal position of the parts, the power head and lower unit together with the connecting drive shaft 15 and 50 exhaust manifold 17 are turnable unitarily for steering, the surfaces 18 and 19 being rotatable with respect to each other about the drive shaft axis as shown in Fig. 5.

I claim:

55 1. In an outboard motor, the combination with a lower unit and power head, of means interposed between said lower unit and power head which are relatively movable in the dirigible movement of said lower unit, said means being 60 together provided with complementary exposed surfaces each of which comprises an extension of the other in the normal position of the parts and with complementary forward and rearward surfaces laterally movable with respect to each 65 other upon the dirigible movement of the lower unit, one of said means being connected with said lower unit to turn therewith.

70 2. In an outboard motor, the combination with a power head and lower unit, of a relatively stationary swivel housing interposed between said power head and lower unit and upon which said outboard motor is dirigible, and a fluid conduit connecting said power head and lower unit externally of said swivel housing and turnable 75 therewith, said conduit and swivel housing hav-

ing smooth exposed surfaces complementary to each other in the normal forward propelling position of the lower unit and conduit and having complementary surfaces permitting the arcuate movement of said conduit about the center on 5 which the outboard motor is dirigible respecting the swivel housing.

3. In an outboard motor, the combination with a dirigible lower unit, of a swivel housing provided with means affording a bearing for the 10 dirigible movement of the lower unit, and a part connected with the lower unit and projecting upwardly at the rear of the swivel housing, said part and swivel housing having complementary 15 side surfaces registering in the normal forward propelling position of the lower unit and complementary forward and rearward surfaces movable laterally with respect to each other upon the occurrence of dirigible movement between the lower unit and swivel housing. 20

4. In an outboard motor, the combination with a smooth wall surfaced lower unit of generally streamlined contour, of a shaft housing connected with said lower unit, an exhaust pipe connected with said lower unit and spaced from said 25 shaft housing, and a swivel housing providing bearings for said shaft housing and extending into close proximity to said exhaust pipe, said pipe and swivel housing having complementary 30 surfaces, together comprising in one position of the parts an upward extension of the wall surfaces of the lower unit, said surfaces being so organized as to permit the dirigible movement of the exhaust pipe with the lower 35 unit and about the swivel housing. 35

5. In an outboard motor, the combination with a power head and lower unit, of a swivel housing having smooth walled contour provided with vertically spaced bearing portions, means providing 40 bearings in said portions for said power head and lower unit, and means connecting said power head and lower unit and movable relatively to said housing in an arc concentric with said bearing means, said connecting means and housing having complementary surfaces laterally formed 45 to be flush with each other in the normal forward propelling position of the housing.

6. In an outboard motor, the combination with a swivel housing, a drive shaft housing journaled 50 therein and a power head and lower unit connected by the drive shaft housing, of an exhaust pipe connecting said power head and lower unit externally of said drive shaft housing and swivel housing and so contoured as to be complementary thereto to comprise a substantially smooth 55 walled composite structure, and means providing a water passage internally of said exhaust pipe for conducting water from said lower unit to said power head about the journals provided for said 60 shaft housing. 60

7. In an outboard motor, the combination with a bracket, of a swivel housing pivotally connected with the bracket and provided with bearings, a propelling unit swiveled in said bearings, a rearwardly projecting means on said bracket spaced 65 at each side of said swivel housing, and a thrust member adjustably connected between said means to receive the thrust of said swivel housing and disposed wholly forwardly of said housing, whereby said housing is freely movable pivotally rearwardly therefrom, the sides of said 70 swivel housing comprising externally smooth walls elongated to a greater distance beyond said bearings in a direction away from the pivotal 75 75

connection with said bracket than in a direction toward said thrust receiving member.

8. In an outboard motor, the combination with a bracket, of a swivel housing pivotally connected with the bracket and provided with bearings, a propeller unit swiveled in said bearings for dirigible movement on an upright axis, a thrust member adjustably connected to transmit the thrust of said unit to said bracket, whereby to limit the pivotal movement of said housing in one direction with respect to the bracket, the housing being freely movable pivotally in a direction aft and

upwardly and having externally smooth side walls elongated to a materially greater distance aft of said axis than forwardly thereof, said unit comprising an upper portion above said swivel housing, a lower portion below said swivel housing, and a tube connecting said portions immediately aft of said housing, said tube having side surfaces complementary to the externally smooth walls of the swivel housing to be substantially flush with said walls in a normal forward propelling position of said unit.

FINN T. IRGENS.
